UNITED STATES PATENT OFFICE.

JAMES R. MCWANE, OF BIRMINGHAM, ALABAMA.

CORE-BAR PUSHER.

1,035,376.

Specification of Letters Patent. Patented Aug. 13, 1912.

Application filed May 16, 1911. Serial No. 627,624.

To all whom it may concern:

Be it known that I, JAMES R. MCWANE, a citizen of the United States, residing at Birmingham, in the county of Jefferson and State of Alabama, have invented a new and useful Core-Bar Pusher, of which the following is a specification.

The invention relates to a core bar pusher.

The object of the present invention is to provide a simple, efficient and comparatively inexpensive core bar pusher of strong and durable construction, capable of exerting great pushing force against a core bar to loosen the same within a pipe after the latter has been cast, and adapted to assist or supplement the action of core bar pulling mechanism, such as disclosed in Patents Nos. 967,039 and 967,041, granted to me Aug. 9, 1910.

A further object of the invention is to provide a double acting reciprocating core bar pusher of this character, designed to be located in the space between two parallel pipe runs, and adapted to operate alternately on the core bars of the pipes of the spaced runs, and equipped with two sets of plungers, connected with each other, whereby the outward core bar engaging or pushing movement of one set of plungers will operate to move the other set inwardly and return the same to their initial position for the next core bar pushing operation.

With these and other objects in view, the invention consists in the construction and novel combination of parts hereinafter fully described, illustrated in the accompanying drawings, and pointed out in the claims hereto appended.

In the drawings:—Figure 1 is a side elevation of a double acting hydraulic core bar pusher, constructed in accordance with this invention. Fig. 2 is a plan view of the same. Fig. 3 is a longitudinal sectional view on the line 3—3 of Fig. 2. Fig. 4 is an end elevation. Fig. 5 is a horizontal sectional view on the line 5—5 of Fig. 3. Fig. 6 is a horizontal sectional view on the line 6—6 of Fig. 3. Fig. 7 is a transverse sectional view on the line 7—7 of Fig. 6. Figs. 8 and 9 are detail views of the inner and outer ends of the cylinders and their supporting stands. Fig.

10 is a vertical longitudinal sectional view on the line 10—10 of Fig. 8. Fig. 11 is a longitudinal sectional view of one of the hollow plungers.

55

Like numerals of reference designate corresponding parts in all the figures of the drawings.

The specification and drawings are a disclosure of one embodiment of the invention, 60 while the claims define the actual scope of the invention.

In the accompanying drawings illustrating the preferred embodiment of the invention, the hydraulic core bar pusher comprises in its construction four cylinders 1, arranged in pairs or sets, the members of each pair or set being preferably cast integral with a supporting stand 2, preferably consisting of a horizontal base 3 and inner 65 and outer transverse supporting portions 4 and 5, but the stands may be of any other preferred construction, as will be readily understood. The two stands 2 are arranged end to end, the cylinders of one stand being 70 disposed in alignment with the cylinders of the other stand, and the inner upright supporting portions 4 of the stands, which are fitted against each other, are secured together by bolts 6, arranged in an elliptical 75 series around the inner ends of the cylinders, suitable perforations 7 being provided in the upright supporting portions 4, as clearly illustrated in Fig. 9 of the drawings. The stands are provided at the bottom or base 80 with depending vertically disposed transverse flanges 8, which engage and partially embrace a supporting block 9 to which the stands are secured by vertical rods 10, but any other suitable foundation may be of 85 course provided for the hydraulic core bar pusher. The rods 10, which pierce the base of each of the stands, are threaded at their upper ends for the reception of nuts, and the bottom or base of each stand is extended at 90 the outer end beyond the outer upright supporting portion and is reinforced by an integral vertical bracing web 11. The inner ends of the cylinders are provided with 95 openings 12, which are threaded for the reception of threaded closure plugs 13.

The cylinders of the two stands are ar-

ranged in the same horizontal plane, and they receive reciprocatory plungers 14 and are equipped at their outer ends with suitable stuffing boxes 15. The plungers are 5 preferably hollow, being provided at their ends with reduced threaded openings 16 for the reception to threaded plugs 17, having annular flanges or heads 18 at their outer ends to fit in corresponding annular recesses 19 and 20 in the ends of the hollow plungers. The annular flanges or heads of the plugs in the outer ends of the hollow cylinders are arranged in flush relation with the outer edges of the said plungers, the depth of the 10 recesses 19 corresponding with the thickness of the annular flanges or heads of the said outer plugs. The recesses 20 in the inner ends of the hollow plungers are of a depth less than the thickness of the heads of the 15 inner plugs, which project slightly beyond the inner ends of the plungers and are adapted to abut against the inner ends of the cylinders. This will prevent the entire area of the inner ends of the plungers from 20 fitting against the inner end walls of the cylinders, and are exposed at portions of such area to the action of the fluid pressure when the inner plugs are in such abutting relation.

25 30 The plungers in each side of the hydraulic pusher are connected by upper and lower exteriorly arranged longitudinal rods 21, secured at their outer ends to vertical cross heads 22, which are mounted upon the outer ends of the plungers 14. The outer ends 23 of the hollow plungers are slightly reduced and are secured within central openings 24 of the cross heads 22, which carry horizontally projecting core bar engaging 35 heads 25. The reduced ends 23 extend into the central openings of the cross heads 22 from the inner faces thereof, and they terminate short of the outer faces of the same, as clearly illustrated in Figs. 3 and 6 of 40 the drawings, and the outer portions of the central openings of the cross heads receive inner annular flanges 26 of the horizontally projecting core bar engaging heads 25. The 45 annular flanges 26 are of a diameter corresponding to the diameter of the reduced outer ends 23 of the plungers, and they are secured within the outer portions of the openings 24 of the cross heads by retaining 50 rings 27. The retaining rings 27, which are fitted against the outer faces of the cross 55 heads, are provided with openings of a diameter to fit the projecting portions of the core bar engaging heads 23, and their inner peripheral portions project inwardly at the 60 central openings of the cross heads and engage with the annular flanges 26 of the core bar engaging heads 25. The said retaining rings are secured to the cross heads by screws 28, which pierce the retaining rings 65 and engage threaded holes or sockets in the

cross heads. The projecting heads 25, which strike the core bars, are preferably constructed of brass, but they may be made of any other suitable material.

The cross heads, which extend upwardly 70 and downwardly from the plungers, are preferably tapered from their sides to their ends, and the terminals 29 of the longitudinal connecting rods 21 extend through suitable openings 30 in the ends of the cross 75 heads, and they are threaded for the reception of nuts 31, arranged in pairs and engaging the inner and outer faces of the cross heads. The faces are provided at the outer ends of the cylinders with suitable bearings 80 32 for the reception of the upper connecting rods, and the said bearings 32 preferably consist of pedestals 33 and caps 34, the pedestals being bolted or otherwise secured to the upper edges of the outer upright supporting portions of the faces. The caps are detachably secured upon the pedestals and form sectional bearings for the upper rods 21. The lower connecting rods pass through alined openings 35 and 36, formed 85 in the inner and outer upright supporting portions of the faces located below the plane of the cylinders. By coupling the plungers of the longitudinally alined cylinders in this manner, the plungers at opposite sides of 90 the hydraulic core pusher are permitted an independent action and the outward core bar engaging movement of one set of plungers operates to move the other set of plungers inwardly and returns the same to their 95 initial position for operation.

The hydraulic core bar pusher is double acting and is designed for use in connection with the foundry plant of my co-pending application, filed Mar. 30, 1911, Serial No. 105 618,015, and it is adapted particularly for use in the space between two opposite pipe runs, and alternately operates on the core bars of the pipes of the said runs. In practice a pair of pipes of one of the pipe runs 110 with the core bars therein will be arranged in front of one end of the hydraulic pusher, and the latter will be operated simultaneously with the core bar pulling mechanism heretofore referred to and will assist or supplement the action of the same, and will enable tight core bars to be easily pulled. The outward movement of one pair of plungers 115 operates through the connecting rods to move the other pair or set of plungers inwardly and to return the same to their initial position to enable such plungers to operate on the core bars of a pair of pipes of the other pipe run. By this operation, the reciprocating double acting hydraulic 120 pusher alternately co-operates with the core bar pulling mechanism of the two duplicate plants, but it will be readily understood that it will operate continuously on the core bars 125 of either pipe run, it being of course neces- 130

sary to move the core bar engaging plungers inwardly after each core bar pushing operation.

The cylinders are provided at their outer sides with opposite ports 37 for the introduction and exhaust of water or other motive fluid. Suitable pipes 38 are connected with the cylinders and are designed to be controlled by a standard, four-way valve, or any other suitable means. The pipes of each set of cylinders alternately become supply and exhaust pipes, and when the motive fluid is being introduced into one set of cylinders, the other set of cylinders is exhausting and vice versa. As the valve for connecting the pipes 38 and for controlling the feed and exhaust to the motive fluid does not constitute a portion of the present invention, illustration thereof is deemed unnecessary.

Having thus fully described my invention, what I claim as new and desire to secure by Letters Patent, is:—

1. A core bar pusher including two aligned cylinders, plungers operating in the cylinders and alternately actuated by fluid pressure, and means arranged exteriorly of the cylinders for connecting the plungers with each other, whereby when one plunger is forced outwardly it will move the other plunger inwardly.

2. A core bar pusher including two aligned cylinders arranged end to end, plungers operating in the cylinders and alternately actuated in their outward movement by fluid pressure, cross heads mounted on the plungers at the outer ends thereof, and spaced longitudinal bars connecting the cross heads, whereby when one plunger is forced outwardly it will move the other plunger inwardly.

3. A core bar pusher including separate sets of cylinders, plungers operating in the cylinders, the plungers of each set being connected together, whereby when one plunger is forced outwardly the other plunger will be moved inwardly, and stands for the cylinders composed of inner and outer supporting portions connected at the top with the cylinders, and a base connecting the upright portions at the bottom of the stands.

4. A core bar pusher including separate sets of cylinders, plungers operating in the cylinders, and stands for the cylinders composed of inner and outer supporting portions connected at the top with the cylinders, and a base connecting the upright portions at the bottom of the stands and provided with depending flanges arranged to engage and partially embrace a foundation.

5. A core bar pusher including sets of cylinders, plungers operating in the cylinders, the plungers of each set of cylinders being connected together, whereby when

one plunger is forced outwardly the other plunger will be moved inwardly, and stands for the cylinders composed of inner and outer upright supporting portions, and a base connecting the supporting portions, the said inner supporting portions being fitted against each other and secured together.

6. A core bar pusher including cylinders, hollow plungers operating in the cylinders and provided at their ends with openings and having recesses at the outer ends of the same, plugs secured in the openings and provided with heads or flanges fitted in the said recesses, and means for connecting the plungers to cause the same to move in unison.

7. A core bar pusher including cylinders, hollow plungers operating in the cylinders and provided at their ends with openings and having recesses at the outer ends of the same, plugs secured in the openings and provided with heads or flanges fitted in the said recesses, the inner plugs projecting from and being of a diameter less than the inner ends of the plungers, and means for connecting the plungers.

8. A core bar pusher including cylinders, plungers having reduced outer ends, cross heads having openings receiving the reduced ends of the plungers, and rods connecting the cross heads for causing the same to move in unison, whereby when one of the plungers is forced outwardly the other will be moved inwardly.

9. A core bar pusher including cylinders, plungers operating in the cylinders and having reduced outer ends, cross heads having openings receiving the reduced outer ends of the plungers, said plungers terminating short of the outer face of the cross heads, core bar engaging heads secured in the outer portions of the openings of the cross heads, and means for connecting the cross heads.

10. A core bar pusher including cylinders, plungers operating in the cylinders and having reduced outer ends, cross heads having openings receiving the reduced outer ends of the plungers, said plungers terminating short of the outer faces of the cross heads, core bar engaging heads provided at their inner ends with flanges fitted in the outer portions of the openings of the cross heads, retaining rings through which the core bar engaging heads project, said retaining rings being secured to the cross heads and engaging the flanges of the core bar engaging heads, and means for connecting the cross heads.

11. A core bar pusher including sets of cylinders arranged in alignment, stands supporting the cylinders, plungers operating in the cylinders, cross heads secured to the plungers and extending upwardly and

downwardly therefrom, upper and lower longitudinal rods connecting the cross heads, the lower rods being extended through the stands, and bearings mounted on the stands and located above the cylinders and receiving the upper longitudinal rods.

In testimony that I claim the foregoing as my own, I have hereto affixed my signature in the presence of two witnesses.

JAMES R. MCWANE.
